United States Patent Office

Des. 204,496
Patented Apr. 19, 1966

204,496

PAIR OF EYEGLASSES

Donald J. McCulloch, Greece, N.Y. (299 McCall Road,
Rochester, N.Y.), and Stanley J. Ragaisis, 170 Locust
Hill Drive, Rochester, N.Y.

Filed June 15, 1965, Ser. No. 85,751

Term of patent 14 years

(Cl. D57—1)

FIG. 1

FIG. 2

FIG. 3

FIG. 4

FIG. 5

FIG. 6

FIG. 1 is a front view of a pair of eyeglasses showing our new design;

FIG. 2 is a side view thereof taken from the right side of the eyeglasses shown in FIG. 1, the side not shown being substantially of the same appearance as the side shown;

FIG. 3 is a top plan view of the eyeglasses shown in FIG. 1;

FIG. 4 is a front view of a modified form of the pair of eyeglasses shown in FIG. 1;

FIG. 5 is a side view of said modified form taken from the right side of the eyeglasses shown in FIG. 4, the side not shown being substantially of the same appearance as the side shown; and

FIG. 6 is a top plan view of said modified form.

We claim:

The ornamental design for a pair of eyeglasses, substantially as shown and described.
